UNITED STATES PATENT OFFICE.

THOMAS M. WHITE, OF AUSTIN, MINNESOTA.

POCKET FINGERPRINTING KIT.

Application filed April 11, 1924. Serial No. 705,749.

To all whom it may concern:

Be it known that I, THOMAS M. WHITE, a citizen of the United States, residing at Austin, in the county of Mower and State 5 of Minnesota, have invented certain new and useful Improvements in Pocket Fingerprinting Kits; and I do hereby declare the following to be a full, clear, and exact description of the invention, such as will enable others skilled in the art to which it 10 pertains to make and use the same.

This invention relates to finger printing devices and kits for containing the necessary tools and equipment for making and 15 examining finger prints.

It is the object of this invention to provide a finger printing kit which will be adapted to contain all of the necessary equipment and will be of suitable size to be 20 carried in a coat or vest pocket.

It is a further object to provide a folding kit which will have means therein for quickly and conveniently making finger impressions on cards detachably carried by one 25 section of said kit.

To these ends, generally stated, the invention consists of the novel devices and combinations of devices herein described and set forth in the claims.

30 The invention is illustrated in the accompanying drawings, wherein like notations refer to similar parts throughout the several views, and in which,

Fig. 1 is a plan view of the kit in open or 35 unfolded position;

Fig. 2 is an end elevation of the invention in folded or secured position;

Fig. 3 is a cross section taken on the line 3-3 of Fig. 1;

40 Fig. 4 is a cross section taken on the line 4-4 of Fig. 1; and

Fig. 5 is a fragmentary section taken on the line 5-5 of Fig. 1.

The invention may be made in many different forms and from many different materials, but the construction of the preferred form illustrated is as follows.

50 A rectangular strip X, of preferably flexible material such as leather, forms the back or cover of the kit. This strip is folded to form two connected sections 6 and 7, which are adapted to be foldable transversely upon each other. A frame 8, preferably of wood or sheet metal, is secured to and covered on 55 its backs and sides by section 6 of the strip

Z and has, at one side of its top, semi-cylindrical grooves 9 adapted to hold several cylindrical containers 10. A retaining strip 9^a, of preferably flexible material, extends transversely over the cylindrical grooves 9, 60 at their lower ends, and is adapted to retain the containers 10 when they are properly inserted between the strip and the semi-cylindrical grooves. These containers are adapted to carry powders of different colors 65 which are sprinkled over prints on different objects to clarify or "raise" the print, so that it may be studied. The other side of the frame 8 is equipped with a countersunk portion 11 in which an ink pad 12 is held. 70 Directly beneath the pad 12, the frame has a longitudinal pocket 13, open at the outer end of the frame 8; into which a magnifying glass 13^a, for use in studying finger prints may be disposed. 75

A cover 14, preferably of flexible material, is provided for the top of the pad 12 having one of its longitudinal edges secured to the adjacent side edge of the frame 8 and having its free edge adapted to slightly overlap 80 the adjacent partition 11^a afforded by the countersunk top portion 11 of the frame.

On the other section of the kit 7, a means for detachably holding a plurality of loose sheets or cards 15 is secured. This means 85 is preferably in the form of an open panel 16 stitched at its lower and side edges to the edges of the strip leaving an unstitched edge at its top portion, whereby the cards 15 may be inserted therein. These cards are preferably ruled into ten portions, each ruled portion being adapted to receive a separate finger print, the top five portions being for the prints of one hand and the lower five ruled portions adapted for the finger prints 90 of the other hand. 95

On the connecting portion of the strip, designated by the numeral 17, holding means are provided, preferably in the form of strips 18, stitched to leave small aligned loops 18^a. Small tools, such as the brush 19 and pointer or ridge counter 20, may be inserted through and carried by these loops. The strip X is extended beyond the lower edge of the holding panel 16 to afford a flap 100 21, which is adapted to fold over the opposite edge of the frame 10 on section 6. Co-operating snap buttons 22 and 22^a are provided on the flap and edge of the frame to secure the kit together in folded position. 105 110

The folded kit is of such size that it may be conveniently carried in a coat pocket and may be quickly unfastened to permit a subject's finger prints to be taken. The subject is preferably seated before a table and the kit folded out in front of him with the protecting cover 14 for the pad folded outwardly. The fingers may then be inked on the pad 12 and successively printed on the 10 topmost card carried in the panel 16, each finger impression being made in its proper ruled portion on said card. Identification matter, such as the name, address, etc., of the person may be written on the back of 15 the card, after the card has been drawn out from the top of the panel.

Oftentimes in detective work, it is desired to clarify or "raise" finger prints left on various objects. To accomplish this, various 20 colored powders are used, which are sprinkled over the natural oil print left on the object. Thus, if the object is black, white powder would be used to "raise" the print, while if the print were on yellow 25 metal, such as brass, a silver colored powder would bring the best results. The containers 10 are adapted to hold such powders and to be disposed in the semi-cylindrical grooves 9 on one side of the frame 8.

30 The kit thus contains all necessary paraphernalia for making, examining and clarifying finger prints and, when folded up, is of such size that it can be conveniently carried in a small pocket.

35 The novel means for making specimen finger prints on the top card carried in the panel 16 permit accurate prints to be taken with full identification of the subject and finger from which each print was taken.

40 It will, of course, be understood that various changes may be made in the form, details and arrangement of parts and materials used without departing from the scope of the invention.

45 What I claim is:—

1. A pocket finger printing kit comprising two connected sections foldable transversely upon each other, and a means on one of said sections for overlapping the edges of 50 and holding in place a plurality of loose sheets whereby the top sheet will be exposed to receive finger impressions and be prevented from moving edgewise.

2. A pocket finger printing kit comprising two connected sections foldable transversely upon each other, an ink pad on the inner side of one of said sections, means on the other section for holding a plurality of loose sheets whereby the top sheet will be exposed to receive finger impressions and means for holding a plurality of tools including a counter and brush.

3. A pocket finger printing kit comprising two connected sections foldable transversely upon each other, an ink pad on the

inner side of one of said sections and also means thereon for holding a plurality of containers for holding print-raising chemicals, and a means on said other section for detachably holding a plurality of loose 70 sheets whereby the top sheet will always be exposed to receive finger impressions.

4. A pocket finger printing kit comprising two connected sections foldable transversely upon each other, one of said sections 75 having thereon an ink pad, and means for holding a plurality of containers and a pocket directly beneath said ink pad for the disposal of a magnifying glass, the other of said sections having thereon an open panel 80 in which a plurality of loose cards may be disposed, the top card of which will always be exposed to receive finger impressions.

5. A pocket finger printing kit comprising two connected sections foldable transversely upon each other, the inner surface of one of said sections having on one side thereof an ink pad and directly beneath said pad a pocket for the disposal of a magnifying glass and having on its other side means for holding a plurality of relatively small containers, the combined height of said pocket and pad being equal to the thickness of said containers and said holding means, the other of said sections having thereon 95 means for holding a plurality of loose cards whereby the top card will be exposed to receive finger impressions.

6. A pocket finger printing kit having in combination a strip forming two sections foldable transversely upon each other with a connection portion therebetween, one of said sections having thereon an ink pad, a cover for said pad, and means for holding a plurality of containers, the other of said sections having means thereon for holding a plurality of loose cards whereby the top card will always be exposed to receive finger impressions, and means on said connection portion for holding a plurality of relatively 100 small tools.

7. A pocket finger printing kit having in combination a strip forming two sections foldable transversely upon each other and a connecting portion therebetween, a frame secured to one of said sections having on one side thereof means for holding a plurality of containers and having on its other side means for securing an ink pad and directly below said means a pocket for the disposal of a magnifying glass, means for detachably holding a plurality of loose cards on the other section whereby the top card will always be exposed to receive finger impressions, and means on said connecting portion for holding a plurality of relatively small tools.

8. The structure set forth in claim 7, and a flap on one end of said strip equipped with fastening means for co-operating with fas-

tening means on the outer edge of said frame and securing the sections together in folded position.

9. A finger print kit comprising relatively swinging sections having thereon means for holding a magnifying glass, means for holding a plurality of containers for print raising chemicals, means for holding a plurality of tools including a brush, 10 and means for holding a plurality of sheets of paper for receiving finger prints.

10. A finger print kit comprising rela-

tively swinging sections, one of said sections carrying thereon an ink pad, and said sections also having thereon means for holding 15 a magnifying glass, means for holding a plurality of containers for print raising chemicals, and means for holding a plurality of tools including a brush for distributing said chemicals and a tool for counting 20 the finger prints.

In testimony whereof I affix my signature.

THOMAS M. WHITE.
